UNITED STATES PATENT OFFICE.

JOHN F. PENROD, OF BLAIRSVILLE INTERSECTION, PENNSYLVANIA, AS
SIGNOR OF ONE-HALF TO WILLIAM N. HAYES AND SIMON C. YOUNG,
BOTH OF SAME PLACE.

RAILROAD-FROG.

SPECIFICATION forming part of Letters Patent No. 351,884, dated November 2, 1886.

Application filed June 26, 1886. Serial No. 206,353. (No model.)

To all whom it may concern:

Be it known that I, JOHN F. PENROD, a citizen of the United States, residing at Blairsville Intersection, in the county of Westmoreland and State of Pennsylvania, have invented 5 certain new and useful Improvements in Railroad-Frogs; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to railways, and particularly to the means for permitting one train to pass from the side to the main track, or vice versa, without imparting any jolt to the cars or any beating down of the track. Heretofore it 20 has been accomplished by what are commonly known as "frogs;" but a gap was left between the intersecting rails, which caused a jolt to the cars and a beating down of the rails on each side of the gap. These difficulties have been 25 obviated by cutting away a portion of the sides of the branch rails, so that their upper ends may overlap the main track, thus presenting a continuous rail for the siding. This has been 30 found objectionable, because it throws an obstruction across the main track, which, if neglected, may cause the derailment of a train moving on the main track.

The object of my invention is to maintain a 35 continuous rail practically on the main and side tracks and allow of the cars passing over each other without any jolt or beating of the rails, and to devise a simple construction for effecting the same, and have the rails of the main and side tracks in the same plane at the point 40 of intersection.

The invention consists in having the wing-rails of a frog made yielding and normally held 45 against the sides of the main rail, which is grooved the depth of the flange of the wheels, as will more fully hereinafter appear, reference being had to the annexed drawings, in which—

Figure 1 is a plan view of a section of track, showing my improvements adapted for side

track only. Fig. 2 is a similar view showing my improvement adapted for main or side track.

Similar letters denote corresponding parts in the respective figures.

The main and side tracks, A and B, respectively, are of ordinary construction. The proximate rails intersect at a point, b, and the main rail, forward of this point, is grooved to the depth of the flange of the wheel. This groove 55 a extends parallel with the branch rail, and gives clearance for the flange of the wheel when 60 crossing the main track, either when leaving or coming upon it. Lapped alongside the main rail are the yielding rails C, which are pivoted at one end close to the main rail, and the other ends are free to be moved to and from the 65 main rail, and are held normal by springs d on rods d', which are located beneath the rails and between the ties. These springs, which may be either push or pull springs, yieldingly 70 hold the rails C against the sides of the main 75 rail. There may be only one yielding rail C, as shown in Fig. 1, or two, as shown in Fig. 2. In the former case it is designed for side track only, in the latter case for use in yard or at such point where the cars are shifted to and fro.

It will be noticed that the second rail C employed in Fig. 2 is a continuation of one of the side-track rails. The ends of the rails C opposite the pivots are curved to one side to permit the flanges of the wheels getting a purchase 80 to force them aside.

In practice the rails C fit close against the main rail opposite the groove a, and the treads of the wheels are sufficiently broad to extend beyond the main rail and fit a purchase on the 85 rails C, so that in going in any direction the tread of the wheel will have a continuous bearing, and when crossing the groove a will have a bearing upon the yielding rail. In Fig. 1 the dotted lines show the position of the yielding 90 rail as it would be when a train would be moving from the side track upon the main track.

D are brackets or stops secured to the ties, for limiting the outward movement of the rails C, and D' are similar brackets for fixedly securing the guard-rails E in place.

The yielding rails may rest directly upon the ties or upon any suitable bed secured upon the ties, as desired.

The grooved rail may be strengthened on each side of the groove by fish-plates bolted to the web of the rail in any suitable manner, as will be readily comprehended.

Having thus described my invention, what I claim, and desire to secure by Letters Patent,
10 is—

1. The combination, with the main and side track having the main rail grooved at the point of intersection, of a rail yieldingly held alongside the rail opposite the groove, substantially
15 as and for the purpose set forth.

2. The combination, with the main and side tracks having the main rail grooved at the point of intersection, of two rails embracing the grooved rail and lapped alongside and yieldingly held close thereto, substantially as and for the purpose set forth.

In testimony whereof I affix my signature in presence of two witnesses.

JOHN F. PENROD.
